UNITED STATES PATENT OFFICE.

GEORGE B. LOUDERBACK, OF COMPTON, CALIFORNIA.

WELL TOOL.

Application filed May 12, 1924. Serial No. 712,735.

To all whom it may concern:

Be it known that I, GEORGE B. LOUDERBACK, a citizen of the United States, residing at Compton, in the county Los Angeles 5 and State of California, have invented a new and useful Well Tool, of which a specification is set forth below.

In this specification, and the accompanying drawing, I shall describe and show a 10 preferred form of my invention, and specifically mention certain of its more important objects. I do not limit myself to the forms disclosed, since various changes and adaptations may be made therein without 15 departing from the essence of my invention as hereinafter claimed; and objects and advantages, other than those specifically mentioned, are included within its scope.

My invention relates to well tools and 20 particularly to bites adapted for deep well drilling, and among its salient objects are; first, to provide a simple and convenient means for adjusting the effective drilling gauge of such a bit to compensate for wear, 25 without removing the tool from the drill hole; second, to supply an automatic cutter-retracting device, permitting the withdrawal of the tool from a hole of smaller diameter than the effective drilling gauge; and, third 30 to accomplish the required gauge adjustment by a slight raising and lowering of the tool in the hole.

My objects are attained in the manner 35 illustrated in the accompanying drawing, in which—

Figure 1 is a longitudinal central section of the complete tool in elevation, except that the cutters have here been removed for illustrative convenience.

Figure 2 is a much enlarged elevation of 40 the lower end of the tool with the cutter arms expanded to the maximum cutting diameter; and

Figures 3, 4, 5, and 6 respectively are 45 cross sections to the same scale as Figure 2, taken on the lines 3—3, 4—4, etc., of Figure 1.

Similar reference numerals refer to similar parts throughout the several views.

For illustrative purposes I have selected 50 a disk bit having a pair of cutting disks 7 journaled on retractile arms 8. The arms project from the lower end of a longitudinally split tool body comprising the 55 similar halves 9 and 10. These halves are suitably recessed to provide accommodation

for the interior working parts, and each has a longitudinal groove 11 to serve as a circulating-water course.

The upper ends of the body halves are 60 of smaller diameter than the lower, and form the neck 12. The halves are assembled face to face by means of a wedge band 13 at the bottom, an intermediate cylindrical screwed-on shell 14, a screwed-on ring 15 65 at the top of the neck, and a pair of through-bolts 16 at the lower extremity. A wedge 17, suitably seated on the exterior of body half 9, serves to tighten up the wedge band. It is retained in position by means of a 70 deformed washer 18 and screw 19.

Above cylinder 14 is a variably bored and interiorly slotted tubular member 20, carrying a spring-packed stuffing box 21 at 75 its upper extremity, and a similar but 80 smaller diameter stuffing box 22 at its lower end. Member 20 is taper-screwed into the top end of cylinder 14, and is fitted with a longitudinally slideable splined plunger 23 carrying a taper-screw "pin" 24 at its upper 85 extremity. The plunger has an axial bore 25 and is normally kept protruding its full extent from stuffing box 21 by means of a compression spring 26. It is machined to 90 fit the various bores of member 20, and is free to slide longitudinally therein, but is prevented from turning in the member by its splines 27. At its lower end the plunger carried an open-bottom cylinder 28, having 95 a pair of interior projecting lugs 29, serving 100 as a part of an escapement mechanism to be described.

The upper ends of disk arms 8 are wedge 105 shape, with rounded extremities, and extend into the body of the tool. They are retained therein by bolts 16 passing through wedge shaped slots in the arms. The upper extremities abut against correspondingly shaped sockets in the body halves, to resist the thrust of the disks when the tool is 110 cutting, and the wedge shaped slots permit the arms to swing about their rounded ends to provide the variable adjustment of the cutting diameter. The arms are held at the desired angular position when drilling by means of the square wedge-shaped head 30 of feed screw 31. When the whole tool is lifted however, the arms are free to drop down upon bolts 16 and in so doing they 115 free themselves from engagement by head 30, and retract toward the axis of the tool.

In Figure 1 the arms are shown in their

fully retracted position but not dropped down upon the through bolts. They are in position to start drilling the smallest diameter hole of which the tool is capable. As 5 the feed screw descends, the arms are forced apart to increase the drilling diameter, and Figure 2 shows the position they assume when drilling the maximum size hole. When thus adjusted, however, the arms are 10 still free to drop down upon the through bolts when the tool is lifted, and in so doing they will come together again as in Figure 1, but in this case they will hang upon the bolts.

15 The feed screw 31 does not rotate, since it is prevented from doing so by its square head. Its neck may also be made square if desired, instead of round as shown. The screw is lowered by turning the flanged 20 feed nut 33. The upper end face of the nut is made in the form of a radial-tooth ratchet 34, engageable by a similar face on the lower end 35 of a deeply bored operating spindle 36. The feed screw in its upper 25 position is nearly wholly within the bore of the spindle, and the latter projects above the neck 12 of the body of the tool through a cupped leather packing washer 37.

Power for operating the spindle and feed 30 nut is supplied by a previously wound-up torsion spring 38, contained in a recess of neck 12. One end of this spring is attached to the spindle and the other to one of the body parts. Its stored energy is released 35 as desired to lower the feed screw by means of an escapement comprising a head 39, having two pairs of lugs 40 and 41 in vertically spaced planes, working in cooperation with lugs 29 of the escapement 40 cylinder. Lugs 40 and 41 are in quadrature relation as shown, and torsion spring 38 turns the operating spindle 90 degrees at each operation of the escapement.

The escapement is worked by alternately 45 raising and lowering the plunger 23. Figure 1 shows the plunger in its upper position where it is normally held by spring 26. In this position the lugs 29 in the escapement cylinder engage lugs 40 of the escapement head as shown most plainly in Figure 50 4. When the plunger is lowered lugs 29 disengage the upper pair of lugs on the escapement head and engage the lower pair 41 after the spindle has revolved 90 degrees 55 under the compulsion of torsion spring 38.

Reaming blades 42 may be added to the tool if desired and do not constitute an essential part of the present invention. In place of these blades, centering devices may

sometimes be substituted to advantage. 60 Circulation passages from end to end of the tool are provided by bore 25, escapement cylinder 28, space 43, and ducts 11.

Having thus fully described my invention in a way that will be clear to those 65 familiar with the drilling art, I claim:

1. A drilling bit comprising; a pair of pivoted cutters; a feed screw adapted for variably spacing said cutters; a torsion spring adapted for actuating said feed 70 screw; and a plunger adapted by reciprocation to cause said spring to act.

2. A drilling bit comprising; pivoted disk cutters on a pair of pivoted arms; a feed screw adapted for variably spacing said 75 arms; a torsion spring adapted for actuating said feed screw; and a plunger within the bit, protruding therefrom, adapted by reciprocation to cause said spring to act.

3. A drilling bit comprising; a pair of pivoted cutters; a feed screw adapted for variably spacing said cutters; a torsion spring adapted for actuating said feed screw; an escapement for controlling the action of said spring; and a plunger adapted by reciprocation to operate said escapement. 85

4. A drilling bit comprising; pivoted disk cutters on a pair of pivoted arms; a feed screw adapted for variably spacing said 90 arms; a torsion spring adapted for actuating said feed screw; an escapement for controlling the action of said spring; and a plunger within the bit, protruding therefrom, adapted by reciprocation to operate said escapement. 95

5. A drilling bit comprising; a pair of pivoted cutters; a feed screw adapted for variably spacing said cutters; a torsion spring adapted for actuating said feed screw; an escapement for controlling the action of said spring; and a plunger adapted by reciprocation to operate said escapement; said cutters being adapted for gravitational retraction when the bit is suspended. 105

6. A drilling bit comprising; pivoted disk cutters on a pair of pivoted arms; a feed screw adapted for variably spacing said arms; a torsion spring adapted for actuating said feed screw; an escapement for controlling the action of said spring; and a plunger within the bit, protruding therefrom, adapted by reciprocation to operate said escapement; said cutters being adapted 110 for gravitational retraction when the bit is suspended. 115

GEORGE B. LOUDERBACK.
